(57) **CLAIM**

The ornamental design for an intramedullary nail, as shown and described.

DESCRIPTION

FIG. 1 is a front perspective view of an intramedullary nail of the new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines show portions of the intramedullary nail that are included for illustrative purposes and form no part of the claimed design.

Color forms no part of the claimed design.
